UNITED STATES PATENT OFFICE.

CHARLES ADAMS-RANDALL, OF NEW YORK, N. Y.

TELEPHONE-TRANSMITTER.

No. 927,395.

Specification of Letters Patent.

Patented July 6, 1909.

Application filed April 16, 1907. Serial No. 368,467.

To all whom it may concern:

Be it known that I, CHARLES ADAMS-RANDALL, a citizen of the United States, residing at New York, in the county of New York and State of New York, have invented new and useful Improvements in Telephone-Transmitters, of which the following is a specification.

In telephony, telephone transmitters, as now generally constructed and used in a local circuit with the battery and primary of an induction coil or transformer, are not adapted, as is well known, to the use of high-tension currents, or currents of high voltage, the practical maximum voltage therethrough rarely exceeding six volts at an amperage usually very small, determined by the resistance of the circuit of which the transmitter is a part. This low voltage has been found to be absolutely necessary to overcome the troubles arising from the use of too high voltage which causes "arcing", "frying", and "heating" in and of the variable resistance of the transmitter, creating disturbing noises in the receiver, affecting the articulation, the adjustment and reliability of the transmitter, and destroying the efficiency of the variable resistance in a very short time.

The object of the present invention is to produce a telephone transmitter having new and novel means and general construction to adapt the same to carry and vary advantageously therethrough a current of high voltage, as compared with the voltage heretofore used and without the above noted disadvantages and defects, and especially overcoming deterioration of the variable resistance, such telephone transmitter, because of the greatly increased voltage carried and varied thereby, being applicable for practical use on longer line and cable circuits than has heretofore been possible with transmitters as now constructed.

To this end the invention generically consists in obtaining greatly increased voltage or watts through a telephone transmitter, by having a variable resistance conductor of low normal resistance and large conductivity or current carrying capacity; supporting said variable resistance *en masse* directly upon a suitable vibrator, such as a diaphragm, or upon or within some part secured to the diaphragm and vibrated thereby; holding and confining *en masse* under pressure, said variable resistance having a materially increased mass of low resistance

and large conductivity within a suitable receptacle and covering this resistance with a thin yielding perforated plate or cover of non-conducting material; having a contact piece or electrode, or electrodes, preferably adjustable, in electrical contact with the mass of resistance granules through a perforation, or perforations, in the said non-conducting plate or cover; and having a single lead or connection from one pole or battery or other source of electrical energy, such as an electric light current supply, to the mass of confined granules, and therefrom by means of a contact piece, or pieces, in electrical variable contact therewith back to the other pole of the battery or other source of current supply, such circuit including, if desired, one of the coils of a transformer, or two or more transformers if two or more contact pieces are used in the construction of the transmitter.

To obtain the increased conductivity of the variable resistance, the granules are arranged in a mass over a comparatively large surface covering, preferably at a suitable uniform depth or thickness, almost the entire surface of the diaphragm or other support carrying the granules, and if such support be used it is attached to the diaphragm and vibrated thereby. The granules are suitably held in place by an annular body, preferably of some pliable material such as leather, paper, soft rubber, or felt of proper thickness, this body surrounding the granules at the outer edge of the mass, and one side, face, or surface of the granules being in electrical contact with the part carrying the same and being the means for making electrical connection to the granules from the battery or other source of electrical energy. The opposite side, face, or surface of the granules is covered, except at the point or points of contact therewith, by a thin yielding or pliable plate of mica, paper, rubber, or other similar non-conducting material having a central perforation, or a number of perforations, formed therein, and further covered by a suitably supported or preferably adjustable contact piece or pieces arranged over the cover and granules and resting on the edge of the perforation or perforations therein, whereby the granules are entirely covered, confined and held under pressure in a mass, the contact piece or pieces being in proper engagement therewith and forming the electrical connection or connections from the

battery to the adjacent side or surface of the granules.

In the drawings: Figure 1 represents a transverse vertical section of the transmitter and the circuit connections in diagrammatic plan. Fig. 2 is a top plan view of a portion of the transmitter. Figs. 3, 4 and 5 are detail views of the transmitter. Fig. 6 is a plan view, partially in diagram, of a modification of the transmitter. Fig. 7 is a detail plan view of a portion of the transmitter shown by Fig. 6.

Similar characters of reference are employed to indicate corresponding parts in the several views.

The numeral 1 represents the case or body of the transmitter, preferably made of hard rubber or other non-conducting material, and is provided with a slightly raised annular seat 2 in the interior thereof which supports an annular washer 3 of soft material, such as paper, rubber, or leather, and on this washer a diaphragm 4 is disposed, the diaphragm being preferably of metal. This diaphragm 4 may be held in place by any suitable means, but it is preferred to use a metal ring 5 having exterior screw-threads as at 5^a and fitting in and engaging the inner screw-threaded surface 6 of the case or body 1. The ring 5 is provided with three or more lugs or projections 7 which bear upon the peripheral edge of the diaphragm at different portions of the latter and by means of which greater freedom of vibration of the diaphragm is obtained than when a clamping means is employed completely engaging the peripheral edge of the diaphragm. An annular receptacle or body 8, formed of suitable pliable material such as soft leather, rubber, felt or the like, is secured to the diaphragm by means of glue, or otherwise, and preferably has an outer diameter nearly equal to that of the diaphragm, the inner diameter of this annular receptacle or body being greatly in excess of the diameter or area of the face of the electrode or electrodes employed in the organization of the transmitter. The body 8 forms a cup, chamber, or holding means having a comparatively large superficial area of such suitable depth as to permit the use of a mass of granular variable resistance material of large conductivity and low normal resistance.

The variable resistance 9, preferably composed of carbon granules, is arranged within the annular receptacle or body 8, the said granules in a mass entirely filling the body or receptacle at a uniform depth. This variable resistance is held and confined under pressure within the annular receptacle or body, *en masse*, by means of a thin yielding perforated cap or cover 10 of soft leather, mica, rubber, paper or other suitable non-conducting material secured at its edge to

the annular receptacle or body 8 by means of shellac, glue, or other material and is also held close to the resistance material by a contact piece 11, as shown by Fig. 1, the said contact piece resting upon the cover 10 over a perforation 12 in the center of the cap or cover, the said contact 11 positively engaging the granules 9 at all times and completing the inclosure for the variable resistance to confine the latter within the receptacle provided by the body 8. The contact piece 11 is carried by a suitable arm 13 attached to the case or body 1 at its outer extremity, as at 14, and having a slight adjustment through the medium of a stiff arm or member 15 also fixed to the case 1 and extending over the arm 13 and carrying an adjusting screw 16 which bears on the inner end or extremity of the arm 13. By adjusting the screw 16 the engaging pressure of the contact piece 11 with relation to the cap or cover 10 and the variable resistance granules 9 may be modified.

A mouth piece 25 is provided which is secured to the case 1 by a screw-thread upon the same fitting into the screw-threaded central opening 26 of the said case.

A suitable cap or cover 27 is applied over the transmitter opposite the mouth piece so that all the parts of the transmitter are fully inclosed, the cover being removable through the medium of screw-threads formed in a portion thereof and engaging corresponding threads on the exterior surface of the case of body 1, as at 28.

The circuit connections with the battery B to and from the transmitter are shown by Fig. 1, and are as follows: A wire *w* runs from the positive terminal of the battery to the primary coil of an induction coil 17, the said primary coil also being connected to the diaphragm 4 and variable resistance 9 by a wire 18 passing through an opening 27^a in the center of the transmitter cap or cover 27. The secondary coil of the said induction coil 17 is connected to line L in the usual manner, as shown by Fig. 1, and also to ground by a wire *w'*. A switch S is used to determine and change the voltage of the current through the transmitter and has thereon a series of buttons A, C, D and E with which a switch arm S' is adapted to operate, and between the pivotal extremity of this latter arm and the arm 13 carrying the contact piece 11 a wire 19 runs to set up the proper electrical connection between the switch and the said contact piece. The buttons A, C, D and E are respectively connected to sections of the battery B by wires 20, 21, 22 and 23. From the foregoing it will be seen that the circuit is from the positive terminal of the battery to the primary coil of the induction coil 17, by wire 18 to the diaphragm and variable resistance 9 in electrical contact with the diaphragm,

through the granules composing the variable resistance to the contact piece 11, through the arm or support 13 and by wire 19 to the switch S and from the latter back to the battery in accordance with the button engaged by the switch arm S'.

As before indicated, the switch S provides convenient means for changing the voltage from maximum or twenty-four volts, for instance, when the button A is engaged by the switch arm S'; eighteen volts when the button C is included in the circuit; twelve volts when the button D has the switch arm thereon; and to six volts when the button E is in the circuit, or *per contra*, increased from the minimum to the maximum, twenty-four volts, as shown, or up to the greatest possible maximum that may be used with a transmitter constructed in accordance with the principles of the improved transmitter.

The switch S, as shown, has but four contact buttons; but it will be understood that the same may have a greater number if required for still further sub-dividing the battery or for use with a battery having a larger number of cells and a greater number of sub-divisions than illustrated by Fig. 1. The invention is not limited to the use of a switch, the latter being shown as a simple illustration of one means for sub-dividing the battery, but in lieu of the switch other means, either automatic or semi-automatic, may be used without departing from the principle involved or to control the subdivisions of the battery to determine the voltage through the transmitter as may be desired.

The transmitter just described and as shown by Figs. 1, 2, 3, 4 and 5, illustrates the simplest and preferred form of the invention. This simplified form of the invention may, however, be varied in many ways, one modification being shown by Figs. 6 and 7 and consisting in providing more than one perforation in the cover or cap 10, the latter in this modified construction having a series of three openings 29 therein to accommodate a corresponding number of electrodes or contact pieces 11^a, 11^b and 11^c carried by supporting arms 13^a, 13^b and 13^c secured to the case 1, as clearly shown by Fig. 6. In connection with this modified form of the invention it is preferred to employ three induction coils 17^a, 17^b and 17^c, connected respectively from one side of the primary coils to the arms 13^c, 13^a, 13^b, and the electrodes 11^c, 11^a, 11^b, the granules 9, the diaphragm 10, and by wire 31 to the battery B, the opposite ends of the primary coils being connected in multiple by a wire 30 to the switch arm S' and from the buttons A, C, D and E to the battery B by wires 20, 21, 22 and 23 in all respects similar in arrangement to the construction shown by Fig. 1. The inside and outside wires of the secondary coil of

the induction coils 17^a, 17^b and 17^c are respectively joined up in parallel and connected to two main lines, or to one main line L from one side or end of the coils, the other ends of these coils being connected to the ground as shown. By this arrangement an increase of power or output over the main line circuit is obtained as the voltage is increased from a minimum of say six volts to a maximum of twenty-four volts; or the voltage may be decreased from maximum to minimum as required or desired.

As heretofore indicated, the important features of the present invention to be particularly noted and compared with other granular transmitters are the extended or increased mass of granules of low normal resistance and increased current carrying or conducting capacity, means for holding and confining the granules in a mass under pressure, and the largely increased surface of the granules as compared with the actual variable surface of the contact or contacts co-operating therewith and in electrical contact with the granules at the contact surface thereof of smallest area. These particular essential features of the invention permit of the effective use of a current of minimum voltage, or a low voltage of six volts or less as generally employed as a maximum in known granular transmitters, and also permit of the practical commercial use of a current at a voltage many times greater than the minimum specified with corresponding increased results, of benefits and advantages hereinbefore noted and particularly producing a greater volume of tone at the receiver and the operation of more difficult circuits, and circuits of greater length than heretofore possible and without the detrimental effects of "arcing", "frying", undue "heating" or deterioration of the variable resistances heretofore experienced in the operation of telephone transmitters.

Having thus described the invention, what is claimed, is:

1. A telephone transmitter constructed and adapted to carry and vary high or low tension currents therethrough comprising a diaphragm or other vibrating medium in electrical contact with and carrying or supporting a confined variable resistance conductor of uniform depth and large conducting capacity, the conductor being held upon the diaphragm or vibrating medium in a mass under pressure, a co-operating electrode or contact means in adjustable electrical contact with the variable resistance conductor, a source of current supply, and connections therefrom to the variable resistance conductor and to the co-operating electrode.

2. A telephone transmitter constructed and adapted to carry and vary high or low tension currents therethrough, comprising a diaphragm or other vibrating medium car-

rying or supporting a confined variable resistance of uniform depth, low resistance and large conducting capacity held in a confined mass under pressure in direct contact therewith, a coöperating electrode in adjustable electrical contact with the variable resistance, and a source of current supply having connections with the variable resistance conductor and the coöperating electrode.

10 3. A telephone transmitter constructed and adapted to carry and vary high or low tension currents therethrough, comprising a diaphragm or other vibrating medium in electrical contact with and carrying or supporting a confined variable resistance granular material of uniform depth, low resistance and large conducting capacity held confined thereon in a mass under pressure, the variable resistance granular material directly contacting with the diaphragm or other vibrating medium, a coöperating electrode in adjustable electrical contact with the variable resistance, a source of current supply having connections with the variable resistance conductor and the coöperating electrode, an induction coil having its primary in circuit with the current supply and the transmitter and its secondary in circuit with the line, and means in circuit in series 15 with the current supply, the transmitter, and the induction coil primary for increasing and decreasing the current supply in said circuit.

4. A telephone transmitter constructed and adapted to carry and vary high or low tension currents passing therethrough, comprising in combination, a diaphragm or other vibrating medium, a variable resistance conductor, a receptacle on the diaphragm or vibrating medium and having a non-metallic cover which is partially open and containing the said variable resistance conductor in a confined mass under pressure, an electrode means in electrical contact with the variable resistance conductor through the partially open non-metallic cover and co-operating therewith and with the diaphragm or vibrating medium, a source of current supply, and connections from the source of 20 current supply to the variable resistance conductor and to the coöperating electrode means.

5. A telephone transmitter having in combination a vibrating medium, a receptacle held by and movable with said vibrating medium and having a non-metallic cover, a variable resistance medium disposed and confined under pressure in the said receptacle in a mass and of low normal resistance 25 and increased current carrying or conducting capacity and having direct contact with the vibrating medium, an electrode or contact piece in electrical contact with the portion of the resistance medium through the cover opposite the portion of said medium

with which the vibrating medium is in direct contact, the resistance medium having a surface largely in excess of that of the electrode or contact piece, a battery means having one pole connected to the electrode or contact piece, and means for connecting the other pole of the battery means with the surface of the variable resistance medium opposite the electrode or contact piece.

6. A telephone transmitter having in combination a vibrating medium, a receptacle on the medium provided with a non-metallic cover which is partially open, a variable resistance medium confined in the receptacle under pressure and exposed to the partially open portion of the cover, the receptacle and variable resistance medium being vibrantly movable with the vibrating medium, one or more electrode devices in direct electrical contact with the variable resistance through the partially open portion of the cover, a battery, and electrical connections between one pole of the battery and the one or more electrode devices and the remaining pole of the battery and the opposite side of the variable resistance.

7. A telephone transmitter having in combination, a vibrating medium, a receptacle held by the vibrating medium and provided with a cover of mica having one or more openings therein, a variable resistance means confined in the receptacle in direct engagement with the vibrating medium, one or more adjustable spring supported electrodes in pressure contact with the variable resistance means through the open cover, a battery or other source of electric energy supply, and means for electrically connecting the variable resistance and the one or more electrodes to opposite poles of the battery.

8. A telephone transmitter having in combination a diaphragm, a receptacle supported and in part formed by the diaphragm and consisting of an annular pad or washer and a perforated non-metallic cover, a variable granular resistance means confined in the said receptacle, an electrode means in contact with the variable resistance means through the perforated cover, a source of electric energy, and electrical connections between the source of electric energy and the variable granular resistance and electrode means, the variable granular resistance having a larger surface area than the electrode means in contact therewith.

9. The combination, in a telephone transmitter, of a diaphragm having a receptacle thereon, a variable resistance material held in a mass within the receptacle and in direct contact with the diaphragm, a perforated cover of nonconducting material on the receptacle, an adjustable electrode in variable electrical contact with the variable resistance material and slightly impinging or bearing on the cover around the perforation and act-

ing with the cover to completely confine the variable resistance material within the receptacle, and a source of electric energy supply in electrical connection with the electrode and variable resistance material.

10. In a telephone transmitter, a vibrating means, a granular variable resistance conductor held confined under pressure, electrode means in contact with said conductor, and means independent of the electrode means and the vibrating means for placing pressure on the resistance conductor.

11. In a telephone transmitter, a vibrating medium, a granular variable resistance con-

ductor, a yielding or pliable non-conducting cover confining the resistance conductor under initial pressure, and electrode means in contact with the resistance conductor and having a smaller area than that of the said resistance conductor.

20 In testimony whereof I have hereunto set my hand in presence of two subscribing witnesses.

CHARLES ADAMS-RANDALL.
